UNITED STATES PATENT OFFICE.

ALEXANDER W. BUTTERWORTH, OF NEW YORK, N. Y.

STRETCHER FOR MECHANICAL-TELEPHONE-LINE WIRES.

SPECIFICATION forming part of Letters Patent No. 399,016, dated March 5, 1889.

Application filed August 6, 1888. Serial No. 282,047. (No model.)

To all whom it may concern:

Be it known that I, ALEXANDER W. BUTTERWORTH, a citizen of the United States, residing at 45 Broadway, New York city, in the 5 county of New York and State of New York, have invented certain new and useful Improvements in Stretchers for Telephone and other Line Wires; and I do hereby declare that the following is a full, clear, and exact 10 description of the invention, which will enable others skilled in the art to which it appertains to make and use the same.

This invention relates to improvements in stretchers for telephone and other line wires.

15 It is well known that telephone, telegraph, and other line wires are subject to expansion or contraction under atmospheric changes, and hence may be closely stretched or taut one day and slack another, according to the 20 state of the weather in respect to temperature. Now, it is essential, particularly in lines dependent upon vibratory action of the wire for satisfactory communication, as in telephones dispensing with the electric current, to have 25 the wire not only tightly but uniformly stretched at all times; but this is impossible without automatic mechanism, as otherwise the ever-changing temperature of the air will necessarily vary the tension of the wire, and 30 with certain systems of telephone, in which a tightly-stretched wire is essential to their operation, would seriously impair, if not wholly destroy, their usefulness when the weather is warm and the wire slack. I overcome these 35 difficulties by providing automatic tension devices which take up or give out slack as may be required, holding meantime a steady and even pull on the wire and keeping it as taut practically as when originally stretched, 40 in the manner hereinafter described.

The drawing shows a tension device consisting of an arm pivoted upon a pole and having an adjustable weight at one end and a bridge-piece at the other supporting several 45 line-wires.

In the drawing, A indicates an ordinary line pole or support, and B a line-wire. I show a series of these wires supported uniformly by the same bridge piece or bar K, and con-

nected therewith by means of insulators of 50 any suitable construction. This bridge piece or bar is in turn supported by a lever or arm, C, pivoted on the pole A between straps D, and attached at one end centrally to the bottom of the bridge-piece. The opposite end 55 of the bar or arm C is screw-threaded and carries a weight, E. This weight is adjustable upon the lever or arm, so as to accommodate it to the varying needs of the line without changing weights and to maintain uniform 60 tension. Several conditions and needs are provided for and met by this construction. In the first place, a bridge-piece may be loaded with, say, only three out of the five wires it is constructed to carry. In this case it will 65 take, say, a certain adjustment of the counter-weight to make the wires taut. Then when the linemen put on the other two wires they have only to adjust the weight outward to counterbalance the additional wires and the 70 same tension upon all is restored. Again, the varying distances between poles suggest need of varying range in the tension mechanism, which my improved construction supplies. By having the counter-weight adjustable 75 greater or less tension can be given the wires that are up, as well as provide for a greater or less number of wires without any change in the tension devices. Another material advantage of this construction is that the slack 80 is taken up by an upward pressure, thus preventing sagging of the wires.

Having thus described my invention, what I claim as new, and desire to secure by Letters Patent, is—

85 A tension device for overhead wires, consisting of a main support, as a pole, a lever pivoted upon the pole, a bridge-piece for carrying the wire attached to one end of the lever, and an adjustable counter-weight on the 90 opposite end of the lever, substantially as set forth.

In testimony whereof I hereunto set my hand this 20th day of July, 1888.

ALEXANDER W. BUTTERWORTH. [L. S.]
